ROTARY KILN

Louis J. Mueller, Martinsburg, W. Va., assignor
to The Standard Lime and Stone Company,
Baltimore, Md., a corporation of Maryland

Application May 11, 1940, Serial No. 334,632

6 Claims. (Cl. 263—32)

This invention relates to kilns of the types used for burning limestone, and for burning certain refractories, cements and fluxes. The invention is in the nature of an improvement upon that described and claimed in my copending application, Serial No. 232,662, filed September 30, 1938, now Patent 2,204,145, dated June 11, 1940.

The material is burned in an inclined rotary tubular kiln, and the purpose of the inventions defined in the prior application and in the present application is to recover waste heat by imparting it to granular material about to be fed to the kiln. Generally stated, the granular material is fed to the kiln from a chamber which extends transversely across the entire area of the kiln near its feed and gas offtake end. The chamber is of limited thickness measured in the direction of the axis of the kiln and is kept full of the material to be fed. The chamber communicates with the kiln through a series of parallel tubular members which are open from end to end, are completely unobstructed and regulate the feed of the material to the kiln in relation to the inclination of the kiln and the rate at which it is rotated.

On the opposite side, the chamber communicates with the offtake through a series of similar and conveniently shorter tubes which have no flow controlling function but which serve as a supporting grid for a reticulated sheet or screen which serves to retain the granular material which is to be fed to the kiln, and at the same time permits the passage of the heated gases to the offtake.

The interposition of this mass of material to be heated in the path of off-flowing gases tends to retard the off-flow of the gases. One feature of the present invention is the enlargement of the diameter of the kiln by the use of conical sections adjacent the chamber so that the effective flow area through the material is somewhat increased.

Another feature of the invention is the proportioning of the length of the tubular passages to their diameter and to the inclination of the kiln as a whole. By such proportioning a consistent or uniform feed definitely related to the rotary speed of the kiln may be had. Consequently, stable operation can be assured simply by proper design.

The rate of feed is a function of the angle of repose of the material to be burned, so that this enters as a factor in the design. Also, the vibration of the kiln incident to its operation introduces a disturbing factor, which varies with

the material being treated. Hence a precise rule cannot be stated. However, it is true that for any given material and inclination of the kiln, the length of the tubes will ordinarily fall between $1\frac{1}{2}$ and $1\frac{1}{4}$ times the transverse dimension of the tubes, and can be determined experimentally.

Another feature of the present invention is the use of an annular chamber which surrounds the transverse chamber first mentioned and is in restricted communication therewith, the parts being so arranged that the central chamber is kept filled at all times, and any empty space which may exist is local to the annular chamber. The effect of this arrangement is beneficial, because it limits, if it does not prevent, inleakage of air. It makes certain that the central chamber, in which the effective heating occurs, is filled at all times.

Another feature of the invention is the construction of the tubular members as cells in a grid, which may be formed of heat resisting steel. Because of the large size of most kilns, it is desirable to cast the grid in a number of sector-shaped sections, six being a desirable number, particularly where the grid offers hexagonal tubes in honeycomb arrangement, that being the preferred construction.

Another feature of the invention is the use of feed hoppers which communicate through trap gates with the annular feed chamber and which turn with this chamber as the kiln rotates. This arrangement, also, assists in resisting the inleakage of air.

Various other features of novelty will become apparent as the description proceeds.

A commercial embodiment of the invention will now be described by reference to the accompanying drawings, in which:

Figure 1 is a view partly in elevation and partly in axial section of the feed end of a rotary kiln equipped with the feeding mechanism according to the present invention.

Fig. 2 is a section on the line 2—2 of Fig. 1.

Fig. 3 is a fragmentary face view of one of the honeycomb grids; and

Fig. 4 is a fragmentary section similar to the portion of Fig. 1 and showing on an enlarged scale how the grids are mounted.

Referring first to Fig. 1, 6 represents the inlet end of a cylindrical rotary kiln which is of known construction and which therefore need not be illustrated in detail. Such kiln comprises a cylindrical shell of considerable length which is mounted to rotate on a slightly inclined axis

and which ordinarily is driven by pinion 7 engaging a ring gear 8 encircling the kiln and fixed thereto. Various means for supporting the rotary kiln are known in the art and no attempt has been made to illustrate supporting means for the kiln.

It will be understood that, as viewed in Fig. 1, the shell 6 of the kiln extends to the left for a considerable distance, such kilns commonly being between 150 and 400 feet in length. The inclination of the axis of the kiln to the horizontal is subject to variation, depending on the material being treated. In ordinary commercial practice the range is between $\frac{3}{8}$ " per ft. and $\frac{3}{4}$ " per ft. In the commercial use of the present invention inclinations of the order of $\frac{1}{2}$ " per ft. are customarily used, but this is subject to variation depending upon the character of the material being burned and the treatment desired.

It will be understood that the slow rotation of the kiln causes the granular material to move from the higher entrance end toward the lower exit end and in its passage the material is burned by flames directed through the exit end of the kiln, in a manner familiar to those skilled in the art. The treated material discharges from the low end of the kiln while the products of combustion flow upward and discharge from the upper or entrance end of the kiln. Thus there is a counterflow relation by means of which material approaching the burning zone receives some heat from the waste gases flowing to the upper end of the kiln. The prime purpose of the present invention is to increase this heat interchange and recover the maximum practicable quantity of heat from the products of combustion.

Near the entrance end of the kiln the shell is flared outwardly, as indicated at 9, thus forming a tapered or conical entrance portion clearly shown in Fig. 1. A portion of the refractory lining of the kiln is indicated at 10 and it is understood that the kiln may be similarly lined. The flared portion 9 of the kiln terminates adjacent an inwardly directed channel flange 11 and from there on is cylindrical to the line 12, after which it is formed with a reduced conical section 13 connected with the off-take 14. Associated with the off-take 14 there is a packed joint 15 designed to permit the kiln to rotate relatively to the intake connection 16 of the fan 17.

A second channel flange 18 is formed within the shell and is spaced in the direction of the off-take 14 from the similar flange 11. Between the flanges 11 and 18 the shell is slotted as indicated at 19, the size of the slots being sufficient to permit ready passage of the granular material to be treated. The reason for slotting the shell between the flanges rather than cutting it away entirely is simply to retain a portion of the shell and thus secure better strength than can be had if the shell is completely cut away. As far as the operation of the kiln is concerned, the use of the slots has no significance, the important thing being to permit feeding from the chamber 28 freely to the chamber 27.

Sustained by the flange 11 is a grid structure 21 (see Figs. 2 and 3) which is formed of heat resisting alloy steel, conveniently by casting. Because of the large size of most kilns it is not ordinarily practicable to form the grid 21 in one piece, and accordingly it is formed in duplicate segmental sections, these sections being indi-

cated in Figs. 2 and 3. These sections are bolted or riveted together as indicated at 22 and when assembled produce a circular grid, preferably of hexagonal or honeycomb pattern, with a circular bounding flange 23 from which project pairs of spaced lugs 24. The lugs 24 straddle the flange 11 and are connected thereto by bolts 25. The sections are first placed and then connected together, as will be obvious.

Similarly mounted on the flange 18 is a grid 26 which conveniently is similar to the grid 21 except that the tubular passages in this grid are preferably made shorter. The grid 21 has a flow controlling function and in this flow controlling function the length of the tubular passages through the grid enters as an important factor. The grid 26 has no flow controlling function. On the contrary it is simply a sustaining means for the screen or reticulated partition 30, also of heat resisting alloy steel, which is mounted against that side of the grid 26 which is remote from the off-take 14. Except for saving of weight and material, the grid 26 could be identical with the grid 21. The use of heat resisting steel for the grids is important, but it is even more important in connection with the screen 30, because the small particles of stone tend to stick to a screen of ordinary steel and soon clog it seriously.

The chamber between the grids 21 and 26 is hereinafter called the feed chamber, but in addition is a heat exchange chamber as herein-after explained. As the kiln rotates, granular material which fills the chamber flows from this chamber through the tubular passages in the grid 21, thence passes to the lower portion of the conical entrance end of the kiln, passing in a shallow stream from that entrance end into the cylindrical main portion 6 of the kiln where the main burning treatment takes place.

The length of the tubular passages in the grid 21 is proportioned to give the desired rate of feed and is a function of the angle of repose of the material being treated and the inclination of the kiln structure. Ordinarily the length of the passage lies between $1\frac{1}{2}$ and $1\frac{1}{4}$ times the transverse dimension of the same passage. The passages are completely unobstructed.

Surrounding the feed chamber 27 and turning with the kiln is a supply chamber 28 which is annular in form and conveniently rectangular in cross section. It may be constructed in any desired manner, its bounding shell being indicated generally by the numeral 29.

Mounted on the periphery of the shell 29 which encloses the chamber 28 are a plurality of feed hoppers 31. Two are shown and are ordinarily sufficient. The number of such hoppers is not vital. The hoppers 31 flare, as shown, and each hopper communicates with the chamber 28 through an opening co-extensive with the inner small end of the hopper.

This opening is controlled by an inward opening gate 32 which is fixed on a rock shaft 33. Fixed to the shaft 33 at one end is an arm 34 with adjustable counterweight 35, the arm extending in such a direction that when the hopper 31 is moving through the upper part of its orbit the counterweight will urge the gate 32 closed. At other times the gate is held closed by the weight of material in the chamber 28. For instance, consider the lower hopper 31 in Fig. 2.

At the opposite end of the shaft 33 from the counterweight lever 34 are a gate opening lever

36 and a gate closing lever 37. The lever 36 is tripped to open the gate 32 at the proper time by means of an inclined cam member 38. The cam member 38 is hinged to a fixed support 39 at 41 and is held upward in its active position by the coil compression spring 42. The purpose of yieldingly mounting the cam 38, as shown, is to permit it to retreat, so that if the chamber 28 is full to a degree that opening movement of the gate 32 is prevented, the parts will not be over stressed and damaged. The gate closing lever 37 operates only in the event that the gate should stick and fail to close. A fixed striker 40 is mounted in such position that it will engage the lever 37 and force the gate closed should the counter weight fail to close it.

Referring to Fig. 2, the kiln turns in the direction indicated by the arrow A. Consequently the material in the chamber 28 is carried up in this chamber and cascades along the dotted line B-B. The space above and to the right of the line B-B is ordinarily empty. Consequently the cam 38 is located in the position indicated in Fig. 2 so that the hopper 31 will always discharge into the empty portion of the chamber 28.

To fill the hopper 31 use is made of a chute 44 to which granular material is fed at a suitable rate. Chute 44 is positioned to deliver to the hoppers 31 at a point about 60° in advance of the trip cam 38 so that the hopper 31 will be charged before the gate 32 commences to open.

Pivoted to the lower end of the hopper 44 is a cylindrical gate 45 with sector shaped shrouds 46. The shrouds are pivoted at 47 on the hopper 44. In Fig. 2 the gate is shown in full lines in its open position, the closed position being indicated in dotted lines.

Pivoted to the gate 45 is an arm 48 which is offset so as to be out of the path of the hoppers 31 but in the path of the striker rod 49 carried by the leading side of each hopper. A stop 50 limits the swing of arm 48 in a counterclockwise direction. As the kiln rotates in the direction indicated in Fig. 2 the rod 49 strikes the arm 48 and the stop 50 limits motion of the arm so that the arm starts to open the gate 45 as the leading portion of a hopper 31 comes under the chute 44. The hinged mounting of the arm 48 and the stop 50 is used simply to prevent damage to the parts in the event that the kiln turns backward, as it sometimes does when being brought to rest. The parts are so dimensioned that gate 45 will be held open only while the hopper 31 is in position to receive a charge from the hopper and closed at all other times. Further the parts are so dimensioned that the hoppers 33 will not be over filled during the period that the gate 45 is held open.

As a practical matter, control is exercised over the rate of supply of material to the chute 44, but the control mechanism is not a feature of the present invention and hence need not be discussed. It should be observed, however, that if any hopper fails to discharge into the supply chamber 28, because the chamber is full, the hopper simply dumps its load as the kiln rotates, thus disposing of any excess feed.

As the kiln is rotated, a hopper 31, arriving in the full line position of Fig. 2, receives a charge from the chute 44. Continued rotation of the kiln brings the hopper 31 to the dotted line position of Fig. 2 where the gate 32 is opened by the action of the cam 38 which overpowers the closing tendency of the counter weight 35. Thus the charge in the hopper 31 is fed to the supply chamber 28.

In the operation of the kiln the supply chamber 28 is kept full at all times, except for a limited space above and to the right of the line B-B. Under these conditions the feed chamber 27 will be kept filled at all times. Rotation of the kiln causes the granular material to feed through the tubular passages in the grid 21 and thence flow in a thin stream down the tubular kiln and through the burning zone.

The waste heat carried by the products of combustion will be effectively transferred to the charge of material in the feed chamber 27 because the products of combustion must pass through this chamber in heat exchanging relation with the granular material which fills it. The products of combustion, thus deprived of the major portion of their heat, pass through the screen 30 and grid 26 to the offtake 14. The offtake fan 17 is provided to insure the necessary draft and should be adequate to overcome the resistance offered to flow of products of combustion through chamber 27.

Since the chamber 27 is kept filled at all times, the tendency of atmospheric air to enter the kiln through a hopper 31 when its gate 32 is open is minimized. The tapered configuration of the kiln shown at 9 increases the area of the chamber 27 and to a considerable extent reduces the resistance to off-flow of the products of combustion.

Substantial economies are effected by the invention because the waste heat is not only recovered but it is applied to heat the charge approaching the burning zone, with the result that the output of the kiln is substantially increased.

While one embodiment of the invention has been described in considerable detail, this is intended to be illustrative and not limiting and various modifications will suggest themselves. For example, while I prefer the hexagonal or honeycomb grid illustrated, this is subject to modification. It has the advantage of strength combined with lightness and freedom from harmful shrinkage strains. For these reasons the hexagonal arrangement appears to be the best that can be devised, but from the standpoint of the operation of the kiln other forms are technically possible and are within the broad scope of the invention.

I claim:

1. The combination of a kiln rotatable on a slightly inclined axis; a feed chamber for granular material to be treated in the kiln, said chamber being concentric with the kiln and extending transversely thereof, communicating with the feed end of the kiln and rotating therewith; a grid controlling supply from said chamber to the kiln and rotating with the kiln and chamber, said grid comprising connected slender webs forming passages substantially parallel with the axis of rotation and large enough to pass the granular material, and of a length between 1½ and 1¼ times the transverse dimension of the passage; supply means serving to keep said chamber filled with granular material; and means for withdrawing hot gases from the kiln through said grid and chamber.

2. The combination of an inclined rotary kiln; a connection at one end for withdrawing gaseous products of combustion therefrom; a feed chamber extending transversely across the kiln and located adjacent the gas off-take end, said feed chamber being bounded by oppositely disposed spaced walls each comprising a grid made up of slender webs forming tubular passages extend-

ing in the direction of the axis of the kiln; screening means sustained by that grid which is near the off-take for preventing discharge of granular material through said grid, and means for supplying granular material into said chamber to maintain said chamber filled.

3. The combination defined in claim 2 in which the grids are of honeycomb formation.

4. The combination of an inclined tubular rotary kiln; means at one end of said kiln for withdrawing gaseous products of combustion therefrom, the kiln being formed with a tapered enlargement adjacent said off-take; a feed chamber extending transversely of the kiln adjacent the large end of said tapered portion, said chamber being defined by oppositely disposed spaced walls extending across the kiln, each wall comprising a grid formed of slender webs which intersect to form elongated tubular passages extending in the direction of the axis of the kiln, a screen sustained by that grid which is adjacent the off-take end, arranged to prevent the escape of granular material to the off-take; means forming an annular supply chamber surrounding said feed chamber and turning with the kiln, there being openings between said chambers to permit the passage of granular material from said annular chamber to said feed chamber; and means for supplying granular material to said annular chamber while the kiln is rotating, the annular chamber serving as a surplus supply and thus assuring continuous complete filling of the feed chamber.

5. The combination of a kiln rotatable on a slightly inclined axis, said kiln having a flaring entrance end rotating therewith; means forming

5 a feed chamber for granular material to be treated in the kiln, said chamber being located in said flaring entrance end and extending transversely across the same; a grid controlling supply from said chamber to the kiln and rotating with the kiln and chamber, said grid comprising connecting slender webs forming passages substantially parallel with the axis of rotation and large enough to pass the granular material; supply means serving to keep said chamber filled with granular material throughout the entire area of said feed chamber transversely of the kiln; and means for withdrawing hot gases from the kiln through said grid and chamber.

10 15 20 25 30 35 6. The combination of a kiln rotatable on a slightly inclined axis, said kiln having a flaring entrance end rotating therewith; means forming a feed chamber for granular material to be treated in the kiln, said chamber being located in said flaring entrance end and extending transversely across the same; a grid controlling supply from said chamber to the kiln and rotating with the kiln and chamber, said grid comprising zigzag slender webs which form polygonal passages substantially parallel with the axis of rotation and large enough to pass the granular material, the zigzag configuration of the webs serving to permit flexure of the webs as an incident to thermal expansion whereby destructive stresses are avoided; supply means serving to keep said chamber filled with granular material throughout the entire area of said feed chamber transversely of the kiln; and means for withdrawing hot gases from the kiln through said grid and chamber.

LOUIS J. MUELLER.
